SCISSORS

Herman L. Kaplan, New York, N. Y.

Application December 20, 1955, Serial No. 39,399

Term of patent 3½ years

(Cl. D22—5)

Fig. 1 is a top plan view of the scissors showing my new design;

Fig. 2 is a side elevational view of the scissors as seen in Fig. 1.

The bottom or side opposite to Fig. 1 is plain and unornamented.

The essential features of the design are shown in full lines.

I claim:

The ornamental design for scissors, substantially as shown and described.
